UNITED STATES PATENT OFFICE.

JOHN NELSON, OF OTTAWA, KANSAS.

CEMENT-KILN.

1,366,586.

Specification of Letters Patent. Patented Jan. 25, 1921.

Application filed March 24, 1920. Serial No. 368,300.

To all whom it may concern:

Be it known that I, JOHN NELSON, a citizen of the United States of America, residing at Ottawa, in the county of Franklin and State of Kansas, have invented certain new and useful Improvements in Cement-Kilns, of which the following is a specification.

The primary object of the invention is the provision of a downdraft kiln adapted for calcining the pulverized cement ingredients for the manufacture of Portland cement, the device being simple in construction, and easy and inexpensive of installation.

A further object of the invention is the provision of a cement kiln adapted for conserving the heat employed in its operation, thereby reducing the cost of producing cement, the arrangement being such as to arrest or baffle the heat waves at the bottom of the kiln preventing the loss of the pulverized particles of cement.

A still further object of the invention is to provide a kiln having a downdraft maintained by upward passage of the products of combustion surrounding the kiln chamber, ready ignition means being arranged as well as an agitated feed for the ingredients to be calcined.

With these general objects in view the invention consists of the novel combination and arrangement of parts hereinafter more fully described in connection with the accompanying drawings, and in which like reference characters designate corresponding parts throughout the several views.

In the drawings,

Figure 1 is a central vertical sectional view taken through the device,

Fig. 2 is a top plan view of one-half thereof, with the feed member removed,

Fig. 3 is a transverse sectional view taken upon line III—III of Fig. 1,

Fig. 4 is a transverse sectional view taken upon line IV—IV of Fig. 1,

Fig. 5 is an enlarged horizontal sectional view taken upon line V—V of Fig. 1, and

Fig. 6 is a transverse sectional view through the stack upon line VI—VI of

Fig. 1.

Referring more in detail to the drawings, my invention comprises a kiln having inner and outer walls 10 and 11 formed of fire-brick or similar material with an updraught space 12 therebetween, while a steel shell or casing 13 surrounds the outer wall 11. The

pulverized Portland cement ingredients to be calcined or burned in the kiln are received through a stack or conveyer discharge-pipe 14 in the circular portion 15 of the cap plate or spider 16, upon the top of the furnace, the conveyer or feeding means for such ingredients being, preferably such as that illustrated in my pending application Serial No. 312,022, filed July 19, 1919, for a method of making Portland cement and calcining kiln therefor, and shown herein, but it being noted that any suitable conveyer mechanism may be employed.

A two-part downdraft burner 17 is placed at the top of the kiln beneath the cap ring 15, with downwardly-projecting nipples 18 leading into the vertical central chamber 19 of the kiln. The spider 16 rests upon the top of the walls 10 and 11 with legs 31 radially projecting from the ring 15, the ends of the legs being secured to the shell 13 by rivet members 32. A mixing pipe 20 for combustible mixture such as gas and air communicates with each section or half of the burner 17, controlled by a valve 21 in each gas supply pipe 27. The lighting of the burner 17 is initially effected by suitable spark plugs 22 carried adjacent the nipples 18 of the two sections of the burner 17 and connected by suitable electric wiring 23 for operation at a distance in a manner that will be readily apparent.

The cement ingredients or other compound enters the chamber 19 through the feed pipe 14 and is acted upon by the intense heat from the burner 17. The inner wall 10 is mounted upon a ring 24 having supporting legs 25 thereby leaving a space at the bottom of the inner wall 10 for the heat and products of combustion to pass into the lower end of the up-draft space 12.

A helical baffle plate or wall 26 is provided in the space 12, whereby the products of combustion from the kiln are carried circumferentially and spirally around the inner wall 10, and within the outer wall from the bottom to the top of the kiln where the same are exhausted through the open top of the space 12. The heat is conserved in this manner, all of the same being utilized in the downdraft calcining chamber 19 so that the entire ingredients entering the top of the kiln are calcined by the flame and heat descending through said chamber 19. This calcined material drops upon crushing rollers 28 beneath the bottom of the chamber 19.

and is discharged in powdered form upon an endless belt conveyer 29 beneath said rolls for conveying to any distant point desired. The flame enters the bottom of the space 12 a suitable distance above the base or wall 30 of the kiln and continuously rises gradually around within the said space 12; thereby maintaining a uniform high temperature within the calcining chamber 19 with the 10 smallest expenditure of gas from the burner 17. The baffle 26 also strengthens the walls 10 and 11 of the kiln which is further rendered more durable by the steel shell 13. The baffle wall 26 may terminate at any 15 desired point at the top of the kiln such as opposite the elevator, as shown, for driving the heat away from the elevator and any adjacent parts such as the motor 38.

An endless belt conveyer 19 having buckets 20 may elevate and dump the ingredients substantially centrally into the top of the kiln so that such elevating and depositing of the powdered ingredients in the upright kiln heated to a white heat by the burner 25 under suitable control further constitutes my method of manufacturing Portland cement.

The up-going portion of the conveyer 19 passes through a tubular member or conduit 32' enlarging into the stack 14 whereby the 30 filled buckets are successively dumped into the stack for feeding to the kiln, the empty buckets 20 descending through an opening 33 in the side of the stack 14. The ingredients for making the Portland cement are pulverized before being taken up by the conveyer 19 such operation being accomplished in any manner such as by grinding in the Griffin mill.

A screen or sieve 34 within the lower inner 40 end of the stack 14 receives the pulverized ingredients which are agitated thereon so as to pass evenly therethrough in a descending shower or mist of the ingredient particles.

An inverted cone 35 is adjustably mounted 45 in the stack 14 by means of arms 36 upon the cone positioned through vertical slots 37 in the stack 14, said arms 36 and cone 35 being retained in their adjusted position by lock nuts 38 threaded upon the arms 36 exteriorly of the stack 14. The electric motor 38 is secured within the cone 35 and protected thereby is a suitably shaped fan or blade 39 upon its power shaft 40 positioned adjacent the upper side of the screen 34 for 50 evenly distributing the pulverized material upon the screen and imparting sufficient agitation thereto for evenly sifting the ingredients through the screen 34 for descent through the chamber 19. Electrical circuit 55 wires 41 for the motor 38 may follow one of the arms 36 through the adjacent slot 37 of the stack 14 to any convenient point for turning on and off the motor as well as regulating the speed of the agitator 39.

60 The mixing pipes or tubes 20, vertically

positioned at the opposite sides of the kiln communicate with the respective sections of the burner 17, the valves 21 simultaneously controlling the supply of gas from the pipes 27 to the tubes 20 and atmospheric air 70 through the damper plate 42. A plate having three quadrant-shaped wings 43 is journaled upon each pipe 27, adapted for opening and closing air inlet openings 44 in the damper plate 42, at the lower end of each 75 tube 20. A valve stem 45 projects from each pipe 27 for controlling the flow of gas therethrough and as a pinion 46 meshing with an arcuate toothed portion or rack 47 upon one of said wings 43. A handle 48 at the free 80 end of the shaft 45 is adapted for convenience in grasping by the fingers for turning the shaft 45 to shift the wings 43 and regulate the admission of air through the openings 44 simultaneously with the regulating 85 of the flow of gas through the pipe 27 to the tube 20.

In this manner, the sections of the burner 17 are supplied with combustible mixture readily ignited by either one or both of the 90 spark plugs 22, the cement ingredients from the conveyer 19 passing through the screen 34 freely descend through the burner 17 to the calcining chamber 19 without any interruption during the operation of the kiln. 95 The flue 14 has a flange 49 at its lower end overlying the spider 16 and mounted upon the inner wall 10 of the kiln, which taken with the connection between the tops of the walls 10 and 11 by the spider arms 31 100 secured to the jacket 13 affords a strong and serviceable construction.

With this construction no true dampers are required and the base of the kiln is sufficiently tight to prevent the escape of products of combustion and not to interfere with the drafts of the kiln. A cupola with elevator, inlet, motor, screen and paddles as illustrated are employed, it being understood that the baffle wall 26 retards the sudden 110 updraft of the products of combustion preventing any fine calcined material from being wasted by exhausting therewith.

An efficient downdraft kiln is provided with the spiral baffle 26 serving the function of a half-closed damper and all the draft and heat being driven in a retarding channel spirally and continuously a number of times around within the space 12, between the walls, a kiln of simple construction and 120 efficient in its operation, is the result. It will be understood that while the form of the invention herein set forth is believed preferable, minor changes may be made therein without departing from the spirit 125 and scope of the invention as claimed.

What I claim as new and desire to secure by Letters Patent, is:

1. A kiln comprising spaced annular walls having a downdraft chamber therein com- 130

5 municating with the space between the walls adjacent the bottom of the kiln and a baffle plate spirally connected between said walls forming an updraft flue outletting adjacent the top of the kiln.

6. A kiln comprising spaced annular walls having a downdraft chamber therein communicating with the space between the walls adjacent the bottom of the kiln, a baffle plate 10 spirally connected between said walls forming an updraft flue outletting adjacent the top of the kiln, a burner in the top of the kiln adapted for projecting flame downwardly therein and controlling and lighting 15 means for the burner operable at a distance therefrom.

7. A kiln comprising an annular wall, mounting legs beneath said wall, an outer wall spaced from the first-named wall forming 20 an outlet passage for the products of combustion, a burner at the top centrally of the kiln and a spiral baffle plate between said walls whereby the products of combustion are led in a helical path upwardly from the 25 bottom to the top of the kiln.

8. A kiln comprising an annular wall, mounting legs beneath said wall, an outer wall spaced from the first-named wall forming an outlet passage for the products of 30 combustion, a burner at the top centrally of the kiln, a spiral baffle plate between said walls whereby the products of combustion are led in a helical path upwardly from the bottom to the top of the kiln with an outlet 35 for the products of combustion adjacent the top of the kiln.

9. A cement kiln comprising spaced inner and outer walls with the inner wall terminating above the bottom of the kiln, a downwardly-projecting burner at the top of the inner wall, the inner wall having a down-draft chamber therein communicating with an updraft chamber between said walls and

a spiral baffle between the walls whereby the products of combustion are led in a spiral 45 path of travel from the bottom to the top of the kiln between the said walls.

10. A kiln comprising outer and inner walls with an updraft space therebetween, a baffle plate spirally arranged within said space 50 within the outflowing path of travel of the products of combustion from the kiln, a screen member for ingredients entering the kiln having portions spanning the tops of said walls and means for supplying ingredients 55 to the screen.

11. A kiln comprising outer and inner walls with a flue passage therebetween and a downdraft chamber within the inner wall, the flue passage being open at the top of the 60 kiln, a baffle spirally arranged in said passage from the bottom to the top of the kiln, a metal jacket surrounding said outer wall, a screen for the incoming ingredients positioned above said chamber and arms projecting outwardly from the screen, upon the tops of said walls with the outer ends of the arms secured to said jacket.

12. A kiln comprising outer and inner walls with a flue passage therebetween and a downdraft chamber within the inner wall, the flue passage being open at the top of the kiln, a baffle spirally arranged in said passage from the bottom to the top of the kiln, a metal jacket surrounding said outer wall, a screen 75 for the incoming ingredients positioned above said chamber, arms projecting outwardly from the screen, upon the tops of said walls with the outer ends of the arms secured to said jacket, burner sections adjacent the top of the inner wall beneath said screen, means for supplying combustible mixture to said sections and air and gas controlling means for said supply means.

13. In testimony whereof I affix my signature. 85
JOHN NELSON.
